UNITED STATES PATENT OFFICE

2,542,496

CARBON HOLDER FOR WRITING MACHINES

Lester K. Fleischmann, Chicago, Ill., assignor to
Standard Manifold Company, Inc., a corpora-
tion of Illinois

Application May 6, 1948, Serial No. 25,495

3 Claims. (Cl. 197—126)

1

This invention relates to a carbon-holding attachment for the carriage of writing machines such as typewriters, billing machines, and the like, and more particularly to a device wherein carbon holding blades are supported cantileverwise on fixed posts.

As is well known in the art, fanfolded continuous form stationery has superposed strips connected to the adjacent strips at one edge, and it is difficult to insert fresh carbon in the conventional carbon holders without opening the connections. One object of the present invention is to avoid such difficulties. While the invention has particular utility when used in connection with fanfold stationery, it may also be used with ordinary continuous form manifold stationery where the strips are not connected.

The primary object of the invention is to provide an improved carbon holder which may be used to anchor carbon strips in fanfold stationery, and will enable the blades to be shifted laterally so that fresh carbon may be introduced.

Another object of the invention is to provide a simple shiftable support for a carbon blade, whereby the blades may be shifted individually and turned slightly about the posts, to facilitate changing carbon strips without removing the blades from the posts.

Still another object of the invention is to provide a simple locking device, on each post, for releasably securing the blades in vertically aligned operative position.

The invention is illustrated in a preferred embodiment in the accompanying drawings, in which—

Figure 1 is a front elevational view of a device embodying the invention; Fig. 2, a plan view of the same, with dotted lines indicating how the stationery is advanced through the device; Fig. 3, a transverse elevational view of the device; Fig. 4, a vertical sectional view, taken as indicated at line 4—4 of Fig. 2; Fig. 5, a perspective view of one of the carbon-holding blades; Fig. 6, a vertical sectional view, taken as indicated at line 6—6 of Fig. 1; and Fig. 7, a fragmentary sectional view, taken as indicated at line 7—7 of Fig. 1.

In the embodiment illustrated, a conventional base member 8, in the form of an inverted U-shaped channel, is provided with the usual studs 9 for attachment to a carbon holder carriage of well known construction. A pair of posts 10 and 11 are secured to the base by means of screws 12. Each of the posts is provided with a vertical series of spaced transversely extending slots or grooves 13 which are adapted to receive and support carbon-holding blades 14.

Each of the carbon blades 14 is provided with an elongated slot 15 which terminates near the center of the blade in a fan-shaped opening 16, so that the opening 16 may be slipped over the

top of one of the posts and the narrow slot 15 brought into engagement with a pair of opposed grooves. Preferably, the blade has a forwardly extending slotted member 17 through which the end of a strip of carbon or the tail of a carbon pack may be inserted and held in interleaved relation with stationary drawn forwardly between the posts 10 and 11, as indicated by the arrows in Fig. 2.

In order to hold the blades in vertically aligned operative position, a simple locking device is provided on each post. The device may be in the form of a pin having a shank 18 with a head 19 adapted to rest on a perforate bracket 20 extending rearwardly from the post. Each of the blades 14 has a perforation 21, and a perforation may also be provided in the base member 8. When the blades are properly inserted and aligned, the shank of the pin may be inserted through the holes in the blades.

As it is impractical to extend the anchored portion of a carbon strip all the way to the connected edge of a fanfold strip, it is preferred to incline the carbon holding blades 14 about five degrees from a line extending between the posts. This is done most easily by having the posts inclined slightly to the rear from a vertical plane between them.

In using the device, the blades can first be removed by means of the slots 16, and a fanfold strip of stationery placed between the posts. The lowermost blade may then be placed back on the post, a strip of carbon attached to the member 17, and the next connected strip laid over the blade. Another blade is then attached to the opposite post, the carbon strip attached, and this procedure is followed until the carbon blades and carbon strips are interleaved between each of the forms. After an advance set of forms has been filled in, in the writing machine, the record forms are held and the carbons retracted by means of the device to the succeeding set of forms. When it becomes desirable to replace a carbon strip, the locking pin is removed and the blade pulled outwardly along the slot 15, so that the member 17 is readily accessible. After the new strip of carbon has been attached, the blade may be pushed back into operative position and locked by the pin. While only three blades are illustrated, it will be understood that additional ones may be used in order to supply carbon for each record copy.

The foregoing detailed description is given for clearness of understanding only, and no unnecessary limitations should be understood therefrom, for some modifications will be obvious to those skilled in the art.

I claim:

1. A carbon-holding device, adapted to be mounted on the traveling carriage of a writing

machine, comprising: a base member provided with a pair of spaced upwardly extending posts between which stationery strips may be led, said posts being provided on opposite sides with vertical series of transversely extending blade-holding grooves; and a plurality of carbon-holding blades, each of said blades having a transversely extending slot to receive one of said posts and support said blade cantileverwise in a pair of opposed grooves in said post.

2. A device as specified in claim 1, in which the transversely extending slot in each blade terminates in an enlarged opening near the center of the blade whereby the blade may be slipped over the post.

3. A device as specified in claim 1, in which the slot in each blade terminates in an enlarged fan-shaped opening near the center of the blade whereby said blade may be turned on the post to facilitate attachment of a strip of carbon to the blade.
